THOMAS A. BALLOU, OF CLEVELAND, OHIO.

Letters Patent No. 73,070, dated January 7, 1868.

IMPROVEMENT IN FRICTION-ROLLERS FOR BAND-SAWS.

The Schedule referred to in these Letters Patent and making part of the same.

TO ALL WHOM IT MAY CONCERN:

Be it known that I, THOMAS A. BALLOU, of Cleveland, in the county of Cuyahoga, and State of Ohio, have invented certain new and useful Improvements in Friction-Rollers for Saws; and I do hereby declare that the following is a full and complete description of the same, reference being had to the accompanying drawings; making a part of this specification, in which—

Figure 1 is a front view.

Figure 2 is a side view.

Figure 3 is a transverse section in the direction of the line $z z$, fig. 1.

Figure 4 will be referred to in the description.

Like letters of reference refer to like parts in the several views.

The nature of my improvement relates to the manner of making friction-rollers for cylinder-saws, &c., so as to prevent the noise, friction, and indentation of the saw when in operation, which is the case with the ordinary ones now in use. This roller A consists of the head A', which is provided with a shoulder, B, fig. 3. On this shoulder, surrounding the head A', is placed raw hide, C, or its equivalent, as shown in figs. 2 and 3, causing the saw to run quieter, truer, and with less friction. On the raw hide, and extending out from the head A' as far as the end of the shoulder, is placed the follower D, which is secured in place by means of the set-screws I, these screws also holding and securing the raw hide in place in connection with the follower and head. E is the hole for the shaft of the roller, which, when in place, is held by the set-screw F. The friction-rollers now in use, being made of metal, as they press against the saw while it is revolving, thus creating friction, will soon indent or form a groove on the interior surface of said saw, and make a rattling, jarring noise while in operation, and also run uneven and irregular. A series of rollers placed inside of a cylinder-saw, H, is shown in fig. 4, which may be operated in the usual way.

By making the rollers as above described, and surrounding the head A' with raw hide or its equivalent, much noise and friction are avoided. As the saw moves round upon the rollers the indenting is prevented, as the raw hide will not wear away the saw, as iron rollers would when used for that purpose. When rollers made with raw hide in this way are used, the saw will run smooth and true, and without so much jarring and noise as when metallic ones are used; and they are much cheaper; and when the raw hide wears away, it can be taken out and new replaced without the expense of a new saw and rollers, as is the case when metallic ones are used.

What I claim as my improvement, and desire to secure by Letters Patent, is—

The roller A, consisting of the head A' and follower-piece D, and pieces of raw hide C, clamped between the head and follower by means of clamp-screws I, all constructed to operate substantially as described.
